UNITED STATES PATENT OFFICE.

WILLIAM H. SAUVAGE, OF BUFFALO, NEW YORK, ASSIGNOR, BY MESNE ASSIGNMENTS,
TO THE ATLANTIC HAND BRAKE CORPORATION, OF BUFFALO, NEW YORK.

ELECTRIC RAILWAY BRAKE.

Refiling of application Serial No. 265,109, filed December 3, 1918, and abandoned March 7, 1920. This application filed June 8, 1920. Serial No. 387,515.

To all whom it may concern:

Be it known that I, WILLIAM H. SAUVAGE, a citizen of the United States, residing at Buffalo, in the county of Erie and State of New York, have invented certain new and useful Improvements in Electric Railway Brakes, of which the following is a specification.

My invention relates to improvements in electrically operated brake apparatus and more particularly to brake apparatus operated by an electric motor. The main object of my invention is to provide an improved, efficient and reliable means for controlling the operation of such a motor whereby the brake pressure applied may be controlled in a most desirable manner. A further improvement of the invention is in the provision of means automatically indicating the extent of which the motor has applied the brakes. A further improvement consists in providing special means for quickly applying the brakes in an emergency. Further and more specific objects, features and advantages will more clearly appear from the detail description given below taken in connection with the accompanying drawings which form a part of this specification.

In the drawing Fig. 1 is a diagram of apparatus embodying the principal features of my invention in their preferred form. Fig. 2 is a transverse vertical section of one of the spring devices shown in Fig. 1 for controlling the motor operating the brakes to stop the motor from operating the brakes when a predetermined brake pressure has been applied. Fig. 3 is a longitudinal vertical section through apparatus adapted to be placed on the motor armature screw shaft whereby the brakes may be applied quickly in an emergency independently of the operation of the electric motor. Fig. 4 is a transverse section taken on a line 4—4 of Fig. 3. Fig. 5 is a detail illustrating a modification of the motor control devices, the left hand end thereof being shown in section taken on the line 5—5 of Fig. 6 and certain other parts being also broken away to more clearly illustrate the same. Fig. 6 is a transverse section taken on a line 6—6 of Fig. 5. Fig. 7 is a diagram illustrating another arrangement of connections for operating the brake motor.

Referring to Figs. 1 and 2, 13 represents a link to one end of which is suitably connected brake rods of brake rigging to which the brakes are connected in any well-known or suitable manner. The other end of the link 13 is pivoted to one end of a lever 14 having its other end pivoted to a nut 15, screw threaded on a shaft 16 rigidly connected with and driven by the armature of an electric motor 17. 18 represents a link having one end pivotally connected to the central part of the lever 14 and its other end pivotally connected to the central part of a lever 19, one end of which is pivoted to a relatively stationary part 20 and the other end of which has a pivotal connection with one end of a piston rod 21 carrying on its other end a piston 22 operating in a piston cylinder 23. 24 represents a relatively long bar having a longitudinal bore 25 therein (see Figure 2) which is connected at one end with the inside of the cylinder 23 by means of a passage 26 so that any fluid in the cylinder 23 compressed by the piston 22 will compress the fluid through the connection 26 and into the bore 25. The cylinder 23 is preferably carried rigidly with the housing of the motor 17 for convenience.

27 represents storage battery having one terminal connected to a contact switch arm 28 by means of conductor 29. The switch arm 28 is adapted to wipe over contacts 49, 50, 51, 52, 53, 54, 55, 56, 57, and 58. The contact 49 is electrically connected to one terminal B of the motor by means of conductor 40. The electric motor is designed to be reversible and the contact 49 is electrically connected with the reverse windings of the motor at terminal B by means of conductor 40.

Carried upon the bar 24 are eight spring control devices 41, 42, 43, 44, 45, 46, 47 and 48. Each of these devices consists of a screw plug 170 screwed into the bar 24 (see Fig. 2) and a cylinder member 171 screwed into the plug 170, in the cylinder portion of which there operates a piston 172 the space 173 below which is connected with the bore 25 by means of the bore 174 in the screw plug 170. The piston 172 is carried by a piston rod 175 and a screw threaded sleeve nut 176 is screw threaded into the cylinder 171 to compress the spring

177 against the upper face of the piston 172. By operating the screw threaded sleeve nut 176 the force with which the spring 177 forces the piston 172 against its bottom seat 178 may be adjusted to any desired value. The sleeve nut 176 is provided with an air vent 119. The piston rod 175 passes loosely through an insulating plate 179 and carries a ring shaped contact 80 adapted to make electrical connection between contacts 81 and 82 when the piston 172 is in its lower-most position. Also carried on the upper end of the piston rod 175 is an electric contact 83 adapted to make electrical connection between the electric contacts 84 and 85 when the piston 172 is raised. The contacts 83 and 80 are insulated from the piston rod 175 and from one another by suitable insulating 20 washers.

Each of the contacts 82 of the devices 41 to 48 inclusive is connected by a common conductor 86 with the terminal A of the motor 17. The contact member 81 of the device 41 is connected by means of a conductor 31 with a contact 51. The contact member 81 of the device 42 is connected by means of a conductor 32 with a contact 52. The contact member 81 of device 43 is connected by means of a conductor 33 with contact 53. The contact member 81 of the device 44 is connected by means of a conductor 34 with a contact 54. The contact member 81 of device 45 is connected by means of conductor 35 with contact 55. The contact member 81 of device 46 is connected by means of a conductor 36 with contact 56. The contact member 81 of device 47 is connected by means of conductor 37 with contact 57 and the contact member 81 of device 48 is connected by means of conductor 38 with contact 58.

When it is desired to apply the brakes the operator moves the switch arm contact 28 so that it engages contact 51. The motor then becomes energized, the circuit being as follows: From one side of the battery 27 through conductor 29, switch contact 28, conductor 31 contacts 81 and 82 of device 41 and conductor 86 to the motor and from the terminal C of the motor through conductor 39 and switch contacts 9 and 10 to the opposite side of the battery 27. The motor armature then rotates to rotate the screw shaft 16, and the nut 15 is forced outwardly thereon causing the brake rigging connected to link 13 to be operated to apply the brakes. This causes a certain pull upon the link 18, and, through the lever 19 and piston rod 21 this is transmitted to the piston 22, the fluid in cylinder 23 being compressed thereby. Any suitable fluid may be used in the cylinder 23 but I preferably use glycerine, castor oil or some other suitable oil, although gaseous fluids may be used if desired. The pres-

sure exerted on the fluid in the cylinder 23 will be exerted through the passage 26 and bores 25 and 174 and upon the lower side of the piston 172 in each of the devices 41 to 48, and when this pressure has reached 70 a predetermined value, say corresponding to 5% of the maximum braking pressure desired to be applied, the piston 172 of device 41 will be raised against the action of the spring 177 and cause the motor circuit to be 75 opened by reason of the ring contact 80 rising and becoming disengaged from the switch contacts 81 and 82. This deenergizes the motor and stops it from further applying the brakes but leaves the brakes applied 80 to the extent of this predetermined pressure.

If it is desired to apply the brakes with greater pressure, say 10% of the maximum braking power required, the switch contact 28 is removed to contact 52 whereupon the 85 motor is again energized through the connections 52, 32 and contacts 80 and 81 and 82 of device 42 and conductor 86. The motor is then again operated to further feed the nut 15 out along the screw shaft 16 thus applying the brakes with greater pressure. This increases the fluid pressure in cylinder 23 and when this pressure has reached the desired value, say 10% of the maximum braking power to be applied, the piston 172 95 in device 42 will be raised to again open the motor circuit and deenergize the motor in the manner above described with respect to device 41, it being understood that each of the devices 41 to 48 is similar to that shown 100 in Fig. 2 and each is operatively connected in the same manner with the bore 25 and cylinder 23.

By further moving the switch contact 28 along the various contacts 53 to 58 inclusive, 105 the motor may be energized through the various conductors 33 to 38 inclusive and the various devices 43 to 48 inclusive respectively, it being understood that in order to open the motor circuit through these devices 110 43 to 48 a graded increase of pressure must be applied through cylinder 23. Thus for example the device 43 may be designed to open the motor circuit when 15% of the maximum braking power is applied and the 115 device 44 when 25% is applied and the device 45 when 40% is applied and the device 46 when 60% is applied and the device 47 when 80% is applied, and the device 48 when 100% is applied.

In case it is desired to apply, say for example 60% of the maximum braking power at the beginning, the switch contact 28 will be moved immediately to the contact 56 whereupon the motor circuit will be closed 125 through device 46 and the motor operated to apply the brakes until 60% of the maximum braking power is applied, when the pressure in cylinder 23 will have reached such a value that piston 172 in device 46 will 130

be raised against its spring to open the motor circuit.

When it is desired to release the brakes, the switch contact 28 is moved to contact 49.

- 5 This causes the battery 27 to be connected with the reverse winding connections in the motor through the conductor 40, the circuit being as follows: From battery 27 through conductor 29, contact 28, contact 49, conductor 10 40 to the reverse winding connections in the motor at terminal B, and from the motor through conductor 39, to the opposite side of the battery.

In case it is desired to stop the motor when 15 thus releasing the brakes but leaving the brakes partly on, the switch 28 is moved to its neutral position onto contact 50. In case, however, the operator should leave the switch contact 28 upon contact 49 and forget

- 20 to move the same to the neutral contact 50 after the brakes have been entirely released, I provide on the nut 15 an arm 90 adapted to engage a switch contact 91 pivoted at 92 and normally spring pressed against a contact 93 so that when the arm 90 engages

25 member 91 it causes the contact 91 to move away from contact 93 and open the motor circuit through the conductor 39, thus automatically deenergizing the motor when the brakes have been entirely released. In case

- 30 the brake link 13 or other connections should become broken and thus render the turning of the motor incapable of applying the brakes and creating pressure in the cylinder 35 23, the motor will turn the screw rod 16 only until the arm 90 engages the contact lever 9, pivoted at 11, forcing it away from contact 10 against the action of spring 12 and thus breaking the circuit through the conductor 39 to open the circuit of the motor. Thus, in case of any such failure of the

40 brakes the motor is automatically stopped after a predetermined number of revolutions thereof.

- 45 In order that the brakes may be operated by hand or by any other mechanical devices without making use of the motor 17 for that purpose I provide on the screw shaft 16 a gear 20 which may be mechanically connected with any well known or suitable operating means for operating the gear to operate the screw shaft 16 to apply the brakes through the brake rigging 13, 14 and 15.

In case it is desired to reverse the motor 55 to release the brakes, without moving the switch arm 28 from contacts 51-58 to contact 49, this may be done by simply pressing a switch contact button 59 so that it electrically connects the switch arm 28 with the stationary contact 60 which is connected by conductor 30, with conductor 40 the current then passing from the battery 27 through conductor 29, switch contact button 59 contact 60 and conductors 30 and 40 to the reverse current connections in the motor.

While this is being done the switch arm may be left on any of the contacts 51 to 58 and, assuming that the brakes are released to a point below that corresponding to the point on which the arm 28 is left, then, upon releasing the button 59 to disconnect from contact 60, the motor will again operate to apply the brakes to the point corresponding to that at which arm 28 is set.

In the arrangement shown in Fig. 1, the 75 apparatus has been illustrated as particularly applying the brakes to the rear wheels of a truck. In case it is desired to apply brakes to the front wheels of the same then instead of pivoting one end of the lever 19 80 to a relatively fixed point 20, brake rigging similar to the brake rigging 13 is connected to the lever 19 in the same manner as this is connected to the lever 14 but extending to the front wheels of the truck.

In case the invention is applied to cars propelled by electric power the motor 17 may be used to apply all the brakes to the car and also instead of using a battery as a source power may be taken from the third 90 rail or trolley to operate the motor 17 as illustrated in Fig. 7, in which 140 represents a trolley wire engaged by a trolley 141 to electrically connect it with a car propelling motor 142 the other side of which is grounded through conductor 143. The conductors 29 may be connected, one to either side of the motor 142 so that when the switch arm 28 is thrown, the motor 17 is connected to receive power from the trolley 140. This 100 arrangement has the particular advantage that should the trolley become disengaged while the car is running, the motor 142 will act as a generator and supply current for operating the motor 17 to apply the brakes 105 until the car is brought to a stop.

By modifications such as these the improvements may be adapted for use on various kinds of trucks and vehicles such as steam railway cars, electric railway cars, automobile motor trucks and trailers drawn by trucks or tractors. In the latter case the 110 brake rigging and the motor operating the same and the devices 41 to 48 may be carried by the trailer while the control apparatus 28, and 49 to 60 may be carried on the truck or tractor to be operated by the operator thereon, a suitable conduit being provided for the connections 31 to 40 extending from the truck or tractor to the trailer.

Whether used on such a trailer or upon any other sort of vehicle it is desirable that the operators know to just what extent the brakes have been applied and I have accordingly provided a set of indicators 71, 72, 73, 74, 75, 76, 77, 78 for this purpose. These indicators may be in form of electric lights or any other suitable form of indicator may be used such as pressure indicators, preferably electric light indicators. The indica-

tors 71 to 78 inclusive are electrically connected by a common connection 87 with a battery 88, the other terminal of the battery being connected by a common connection 89 with the various contacts 84 in the devices 41 to 48 inclusive respectively. The other terminal of the indicator 71 is connected by conductor 61 with the contact 85 of device 41 and in the same manner the other terminals of indicators 72 to 78 inclusive are connected by conductors 62 to 68 inclusive with the contacts 85 of devices 42 to 48 inclusive respectively. Accordingly when any one or more circuits responsive to the corresponding brake pressure are applied they will cause their contacts 83 to make electrical connections between their contacts 84 and 85 thus closing the circuit through the corresponding indicating devices 71 to 78 inclusive respectively. And so when one or more of the indicating devices 71 to 78 inclusive are energized they indicate to the operator to just what extent the devices 41 to 48 have been operated and accordingly one knows to just what extent the brakes have applied. It will be understood that the indicators 71 to 78 inclusive as well as the batteries 88 and 27 may be carried upon the truck or tractor in case the apparatus is designed to operate brakes on a trailer.

Referring to Figs. 3 and 4, I there show an arrangement for quickly applying the brakes in case of an emergency. In this arrangement the screw nut 15 has integrally connected therewith a sleeve 100 open at one end. Arranged on the sleeve 100 is a sliding sleeve 101, the two sleeves being arranged to slide longitudinally with respect to one another but prevented from rotation with respect to one another by a key 102. The sleeve 101 is provided with a head 103 at its end opposite the nut 15, and between the head 103 and nut 15 there is compressed a spring 104. In order to prevent the compressed spring 104 from moving the sleeve 101 away from the nut 15, a split nut having its two sections 105 and 106 engaging the screw shaft 16, is arranged against the outside of the head 103. The sections 105 and 106 are provided with extensions 107 and 108 respectively adapted to slide in guideways 109 and 110 in frame work rigidly secured to the sleeve 101. Levers 111 and 112 have their long arms normally pulled together by spring 113 to force the sections 105 and 106 toward one another and into engagement with the shaft 16. The short arms of the levers 111 and 112 are pivotally connected with the plunger armature 114 of an electric magnet 115.

The spring 104 is of such size and under such compression that when released it may apply the brakes with the maximum braking power that would be desired on any occasion as for example in an emergency.

When it is desired to apply the brakes in an emergency and quickly, without waiting for the motor to operate, the circuit 115 is energized in any suitable manner which causes the plunger 114 to be moved toward the split nut and against the action of spring 113 to move the sections 105 and 106 of the split nut from the shaft 16. This causes the spring 104 to be released and the sleeve 101 to be forced quickly outwardly along the shaft 16, carrying with the head 15 to which the lever arm 14 in this instance is pivotally connected, so that the lever arm 14 is operated to apply the brakes in an emergency manner. When it is desired to reset the spring 104 the motor 17 is operated as to apply the brakes whereupon the nut 15 will be forced outwardly along the shaft 16 to again compress the spring to its normal condition and when it has reached this condition, the magnet 115 is deenergized and the split nut will engage the shaft 16 to lock the spring 104 in its normal compressed condition. The brakes may then be released by reversing the motor in the manner above indicated. In case it is desired to lock the split nut to the shaft 16 so as to prevent the magnet 115 from operating the same, I provide a locking lever 116 which may be swung upwardly as shown in full lines in Fig. 3 and thus prevent the lever 112 from swinging downwardly to remove the split nut section 106 from the shaft 16. By its connection with the lever 112, the lever 111 is similarly prevented from removing its section 105 from the shaft 16. A leaf spring 117 prevents the locking lever 116 from jolting or otherwise being removed from its locking position, unless the leaf spring 117 is pressed in when it may be moved to inoperative position as shown in dotted lines in Fig. 3.

Referring to Figs. 5 and 6 I there show a modified form of devices 41 to 48 inclusive. In this instance the bar 24 is somewhat differently shaped in cross section as shown in Fig. 6, but is still provided with the longitudinal bore 25. The top face of the bar 24 is recessed at various places to provide recesses 120 and shoulders 121 on which are laid diaphragms 122, held in place against the shoulders 121 by rings 123 and cylinder members 124 screwed down thereagainst. The diaphragms 122 normally make contact with contact buttons 125 to which are connected the conductors 31 to 38 inclusive respectively. The buttons 125 and their connections being suitably insulated from the bar 24 as illustrated in Fig. 6. The diaphragms 122 are suitably grounded and connected with the conductor 86. Operating within the cylinders 124 are small pistons 126 normally pressing the diaphragms 122 against the buttons 125 by means of springs 127. Nuts 128 are screw

threaded into the cylinders 124 for adjusting the pressure with which the springs 127 force their pistons 126 against their seats. Screw threaded caps 129 are provided for keeping out dust and dirt and locking the nuts 128 in their adjusted positions. Pistons 126 are provided with piston rods 130 around which the springs 127 are coiled, the piston rods extending through and having sliding engagement with the nuts 128. The spaces 120 beneath the diaphragms 122 are each connected with the bore 125 by means of short bores 131.

The springs 127 are so designed and set that their corresponding pistons 126 will be forced upwardly responsive to various pressures exerted in the fluid cylinder 23 and upon the fluid in 25 and 131 and spaces 120, so that the devices 41 to 48 inclusive will operate responsive to various brake pressures applied to deenergize the motor in substantially the same manner as the devices illustrated by Fig. 2, and shown with their connections in Fig. 1.

25 While I have described my improvement in great detail and with respect to certain embodiments thereof, I do not desire to be limited to such details and embodiments since many changes and modifications may 30 be made and the improvements embodied in widely differing forms without departing from the spirit and scope of the invention in its broader aspects. I desire to cover all combinations of elements or their equivalents 35 set forth in any one or more of the appended claims.

What I claim as new and desire to secure by Letters Patent is:

1. The combination with brake rigging, 40 of an electric motor connected to operate said brake rigging to apply the brakes thereof, and means for automatically stopping the motor from operating the brakes dependent upon the brake pressure applied, 45 said means including a plurality of devices each operating respectively responsive to various brake pressures applied, to automatically stop the motor from operating the brakes.

50 2. The combination with brake rigging of an electric motor connected to operate said brake rigging to apply the brakes thereof, and means for automatically stopping the motor from operating the brakes dependent upon the brake pressure applied, 55 said means including a plurality of devices operating respectively responsive to various brake pressures applied, and switches controlled by said devices respectively for automatically stopping the motor from operating the brakes.

60 3. The combination with brake rigging, of an electric motor connected to operate said brake rigging to apply the brakes thereof, and means for automatically stop- 65 ping the motor from operating the brakes dependent upon the brake pressure applied,

70 said means including a plurality of independently operable spring pressed devices, operating respectively responsive to various brake pressures applied and switches controlled by said devices respectively for automatically stopping the motor from operating the brakes.

4. The combination with brake rigging, 75 of an electric motor connected to operate said brake rigging to apply the brakes thereof, and means for automatically stopping the motor from operating the brakes, said means including a plurality of independently operable spring pressed devices and switches controlled by said devices respectively for automatically stopping the motor from operating the brakes.

5. The combination with brake rigging, 85 of an electric motor to operate said brake rigging to apply the brakes thereof, and means for automatically deenergizing the motor dependent upon the brake pressure applied, said means including a plurality 90 of independently operable spring pressed devices, each operating respectively responsive to various brake pressures applied and switches controlled by said devices, respectively for automatically opening the motor 95 circuit.

6. The combination with brake rigging, of an electric motor connected to operate said brake rigging to apply the brakes thereof, and fluid pressure means acting responsive to variations in brake pressure applied for automatically stopping the motor 100 from operating the brakes.

7. The combination with brake rigging, of an electric motor connected to operate 105 said brake rigging to apply the brakes thereof, fluid pressure means, the fluid pressure of which varies responsive to variations in the brake pressure applied, and a plurality of devices operating respectively 110 responsive to various pressures in said fluid pressure means, for automatically stopping the motor from operating the brakes responsive to various brake pressures applied.

8. The combination with brake rigging, of 115 an electric motor connected to operate said brake rigging to apply the brakes thereof, fluid pressure means acting responsively to variations in brake pressure applied, a plurality of switches operated thereby at different brake pressures applied respectively, 120 and means whereby operation of said switches causes the deenergization of the motor.

9. The combination with brake rigging, 125 of an electric motor connected to operate said brake rigging to apply the brakes thereof and fluid pressure means acting responsively to variations in brake pressure applied, a plurality of switches operated thereby at 130

different brake pressures applied respectively and means whereby operation of said switches causes the deenergization of the motor, said switches being held in normal 5 position by springs with different pressures, respectively.

10. The combination with brake rigging, of a reversible electric motor, a screw shaft driven thereby for operating the brake rigging to operate the brakes thereof, fluid pressure means operating to measure the pressure with which the brakes are applied, and a plurality of devices controlled thereby and acting to deenergize the motor at 15 various brake pressures applied respectively.

11. The combination with brake rigging, of a reversible electric motor, a screw shaft driven thereby for operating the brake rigging to operate the brakes thereof, fluid 20 pressure means operating to measure the pressure with which the brakes are applied, and a plurality of devices controlled thereby and acting to deenergize the motor at various brake pressures applied respectively, and 25 means whereby said screw shaft may be operated to apply the brakes without energizing said motor.

12. The combination with brake rigging of an electric motor operating said brake 30 rigging to apply the brakes thereof, fluid pressure means for automatically regulating the pressure of the brakes whereby the motor may be stopped, and means whereby the brakes may be applied without energizing 35 said motor.

13. The combination with brake rigging of an electric motor operating said brake rigging to apply the brakes thereof, and means indicating the extent to which the 40 brakes are applied by said motor.

14. The combination with brake rigging of an electric motor operating said brake rigging to apply the brakes thereof with various pressures and electric means indicating the pressure with which the brakes 45 are applied.

15. The combination with brake rigging, of an electric motor connected to operate said brake rigging to apply the brakes 50 thereof, means for automatically stopping the motor from operating the brakes dependent upon the brake pressure applied, said means including a plurality of devices operating respectively responsive to various 55 brake pressures applied, to automatically stop the motor from operating the brakes, and indicators controlled by said devices respectively for indicating the extent to which the brakes are applied.

60. 16. The combination with brake rigging, of an electric motor connected to operate said brake rigging to apply the brakes thereof, means for automatically stopping the motor from applying the brakes 65 respectively to variations in brake pressure applied

and with various brake pressures applied and means controlled by said last mentioned means for indicating the extent to which the brakes are applied.

17. The combination with brake rigging, 70 of an electric motor connected to operate said brake rigging to apply the brakes thereof, and fluid pressure means acting responsive to variations in brake pressure applied for automatically stopping the motor 75 from operating the brakes and means controlled responsive to the operation of said fluid pressure means for indicating the extent to which the brakes are applied.

18. The combination with a brake rig- 80 ging, of an electric motor for operating the same to apply the brakes thereof, means for automatically regulating the pressure of the brakes whereby the motor is stopped, a normally compressed spring, and means where- 85 by said spring may be released to apply the brakes independently of the above mentioned motor and whereby said motor may be operated to compress said spring to its normal condition. 90

19. The combination with brake rigging of an electric motor for operating the same to apply the brakes thereof, a normally in- 95 operative spring, and means for rendering said spring operative to apply brakes inde- 95 pendently of the operation of said motor and means for rendering said last mentioned means inoperative to cause the said spring to apply the brakes.

20. The combination with brake rigging 100 of an electric motor for operating the same to apply the brakes thereof, a normally compressed spring and means whereby said spring may be released to apply the brakes independently of said motor and whereby 105 said motor may be operated to compress said spring to its normal condition, said last mentioned means including a screw shaft operated by the motor, a split nut cooperat- 110 ing with said shaft to hold said spring compressed, and electric means for operating said split nut to release said spring.

21. The combination with brake rigging, of an electric motor connected to operate said brake rigging to apply the brakes 115 thereof, and means for automatically stopping the motor from operating the brakes dependent upon the brake pressure applied, said means including a plurality of devices each operating respectively responsive to 120 various brake pressures applied, to automatically stop the motor from operating the brakes, and means automatically stopping the motor after a predetermined number of revolutions thereof. 125

22. The combination with brake rigging, of an electric motor connected to operate said brake rigging to apply the brakes thereof, and fluid pressure means acting responsive to variations in brake pressure ap- 130

- plied for automatically stopping the motor from operating the brakes, and means automatically stopping the motor after a predetermined number of revolutions thereof.
- 5 23. In a vehicle brake system the combination of brake rigging, an electric motor connected to operate said brake rigging to apply the brakes thereof, fluid pressure means acting responsive to variations in 10 brake pressure applied for automatically stopping the motor from operating the brakes, a vehicle propelling motor and connections therefor to a trolley or the like, and connections from said brake motor to 15 said trolley or the like and said propelling motor arranged to normally supply the brake motor from the trolley or the like and from the propelling motor as a generator should the trolley become disconnected.
24. In a vehicle brake system the combination of brake rigging, an electric motor connected to operate said brake rigging to apply the brakes thereof, means automatically stopping the motor from operating the 20 brakes dependent upon the brake pressure applied, said means including a plurality of devices each operating respectively responsive to various brake pressures applied, a vehicle propelling motor and connections 25 therefor to a trolley or the like, and connections from said brake motor to said trolley or the like and said propelling motor arranged to normally supply the brake motor from the trolley or the like and from the propelling motor as a generator should 30 the trolley become disconnected.
- 35

In testimony whereof I affix my signature.
WILLIAM H. SAUVAGE.
